UNITED STATES PATENT OFFICE.

PETER O'HARA, OF OHARA TOWNSHIP, ALLEGHENY COUNTY, PENNSYLVANIA.

GOLF-CLUB.

1,299,014.

Specification of Letters Patent. Patented Apr. 1, 1919.

Application filed July 5, 1917. Serial No. 178,554.

To all whom it may concern:

Be it known that I, PETER O'HARA, a subject of the King of Great Britain, residing in Ohara township, Allegheny county, Pennsylvania, have invented a new and useful 5 Golf-Club, of which the following is a full, clear, and exact description, reference being had to the accompanying drawings, forming part of this specification, in which—

10 Figure 1 is a front elevation of the head of a golf club constructed in accordance with my invention.

Fig. 2 is a top plan view, partly broken away.

15 Fig. 3 is a cross section on the line III—III of Fig. 2, and

Fig. 4 is a view similar to Fig. 3 showing the driver.

20 My invention relates to golf clubs having wooden driving heads, and is designed to provide a wooden club head which will give improved results to the player. To that end 25 my invention consists in providing a bulged playing face on the wooden head of the club, combined with a weight whose length is at least the length of the intermediate portion of the playing face. It also consists in further details of shape and construction 30 hereinafter referred to and claimed. In the drawings, referring to the form of Figs. 1, 2 and 3, 2 is the head of a brassy having the usual brass bottom plate 3, which in the 35 form shown is secured by screws 4 extending through a bottom fiber plate 5. The playing face 6 of this club is bulged longitudinally of the face, as shown in Fig. 2, and is also preferably bulged transversely of the face, as shown in Fig. 3.

40 The weight 7, which consists preferably of lead run into a slot in the back face of the club with the usual screw threaded holes extending inwardly therefrom, extends for a length at least as long as the intermediate portion of the playing face. This intermediate portion at the juncture between the wood and the fiber is about two and one-eighth inches long.

45 The object of thus lengthening the load or weight is to cause the ball to be driven straight ahead, although the club face may strike it toward the outer ends of the curved playing face. The extension of the weight back of the intermediate portion of this face for its entire length causes this desired action. At the same time the bulging of the

face causes a less amount of the surface of the playing ball to contact with the club as it flattens at the moment of impact, and thus lengthens the drive.

I also preferably make the club head 60 longer and narrower than in the usual practice with wooden clubs, the playing face being preferably two and one-half inches long at a point midway of its height, and the total width of the club being preferably not 65 over approximately two and one-quarter inches.

70 In Fig. 4 I show the driver, which is the same in general as the brassy, except for the brass plate.

75 In loading the brassy, however, I preferably extend the loading downwardly and inwardly, as shown in Fig. 3, to give more lift to the ball; while in the driver I preferably extend the loading upwardly, as shown in Fig. 4, to give a top spin to the ball and cause it to run farther after it strikes the ground.

80 The convex playing face also tends to give the correct spin to the ball and corrects slicing, and the length of the face also aids in this action. If the ball is hit on the toe of the club there is sufficient weight behind this portion to prevent slicing.

85 The advantages of my invention will be obvious to golf players, as a better spin is given to the ball, there is less tendency to slicing and pulling the ball, and better accuracy afforded.

90 I claim:

1. A wooden golf club head having a playing face bulged both longitudinally and transversely, the back side of the head having a weight extending for a distance at least approximately equal to the intermediate portion of the playing face, substantially as described.

95 2. A wooden golf club head having a playing face bulged both longitudinally and transversely, the back side of the head having a weight extending along its face for a distance at least approximately equal to the intermediate portion of the playing face, the length of the playing face at its mid-height being at least two and one-half inches, substantially as described.

100 3. A wooden golf club head having a playing face bulged both longitudinally and transversely, the back side of the head having a weight extending along its face for a 110

distance at least approximately equal to the intermediate portion of the playing face, the length of the playing face at its mid-height being at least two and one-half inches, 5 and the width of the club being not over approximately two and one-quarter inches, substantially as described.

4. A wooden golf club head having a back weight extending into the head of the club

at an angle to the horizontal, substantially 10 as described.

5. A wooden golf club head having a fiber bottom plate and a back weight extending into the club head at an angle to the horizontal, substantially as described. 15

In testimony whereof, I have hereunto set my hand.

PETER O'HARA.
